MEANS OF ENGRAVING DIES

Henry L. Pitman, Westfield, N. J., assignor, by
mesne assignments, to Ralph C. Coxhead Cor-
poration, New York, N. Y., a corporation of
Delaware

Original application March 19, 1931, Serial No.
523,920. Divided and this application Novem-
ber 15, 1932, Serial No. 642,751

15 Claims. (Cl. 90—13.1)

This invention is a division of my application Serial No. 523,920, filed Mar. 19, 1931, now Patent Number 2,010,036. It relates to means of engraving dies used in making a type carrier or shuttle of the kind illustrated in my application, Serial No. 523,919, filed Mar. 19, 1931.

A feature of the invention relates to means for engraving a plurality of types in segmental die sections which are subsequently used to produce 10 types of a segmental type shuttle for typewriting machines.

Other features and advantages will hereinafter appear.

In the drawings which form part of the specification.

Fig. 1 is a front view, partly in section, of the die showing two shuttles therein;

Fig. 2 is an end view of the interior of the die unit at the right in Fig. 1;

Fig. 3 is a top plan view of a portion of the die engraving means;

Fig. 4 is a vertical section taken on the line 4—4 of Fig. 3;

Fig. 5 is a side elevation of the fixture for supporting and adjusting a die section in the engraving machine;

Fig. 6 is an end elevation of Fig. 5;

Fig. 7 is a sectional view of a portion of one of the die sections; and

Fig. 8 is a top plan view of a partly formed shuttle.

Similar reference characters represent similar parts throughout the several views.

The die 31 comprises detachable sections 32, 33, 34 and 35, which may be assembled, in a manner hereinafter described, and it may then be supported by the jaws 36 of a stationary chuck. The sections, after they are assembled, form a circular aperture 30 into which are placed one or more partly formed shuttles 29 (Fig. 8). Suitable roller means, not shown, are then inserted into the die aperture 30 and reciprocated by suitable means to flow the metal of the body part 26 of the shuttle into types 42 (Figs. 1 and 7) in intaglio in said die, to form types 43 on the convexed face of the type shuttle, the type intaglios 42 being engraved in the surface bordering the aperture 30 of the die.

The die sections 32, 33, 34, and 35 are rigidly held together and are interlocked to prevent accidental shifting thereof relatively to each other. For this purpose each of the die sections is provided with cross tongues 51 and 52 (Figs. 1 and 2) which fit into corresponding grooves 53 and 54 of the adjoining section to thus locate the

sections with respect to each other so that the ends of their curved surfaces are flush with those of the adjoining sections, and so that the rows of types on the various die sections align. The tongues and grooves also prevent radial and lateral shifting of said die sections since they are at right angles to each other. After the die sections have been assembled they may be secured to each other by a flange or ring 55 (Fig. 1) which is detachably mounted on the die by screws 57.

After the flange 55 is attached to the die two partially formed shuttles 29 are placed into the aperture 30 thereof, each being located laterally in a channel 58 (Fig. 2) formed by inwardly extending flanges 59 on the die sections; said shuttle blanks being located circumferentially of the aperture by gauge blocks 60 located in slots 61 and extending across the channel 58.

Another flange (not shown) similar to the flange 55, is subsequently secured to the opposite face of the die. The flange 55 and its companion are provided with grooves to conform with the shape of the flanges 27 and 28 of the shuttle blanks and into which the shuttle flanges fit. Thus it will be understood that the shuttle blanks are firmly secured in the die after the ring like flanges are secured thereto, to assist in preventing accidental shifting of the shuttle blanks while being acted upon by the roller means. Each shuttle is provided with a complete font of type which is divided into two groups, the types on one shuttle being formed by complementary die sections 32 and 33, Fig. 1, each section forming one of the groups of types, the types on the other shuttle being formed similarly by the complementary die sections 34 and 35.

The die sections 32, 33, 34, and 35 are engraved individually and for this purpose each may be mounted on a fixture 100 comprising a bracket 40 101 which may be secured by clamps 102 to a work-table 103 of an engraving machine similar to the one disclosed in the patent to Taylor No. 542,902, dated July 16, 1895.

Type patterns 104, of which there is one for each type to be engraved in the die, are flat and are secured, one at a time, in a fixture 105 (Figs. 3 and 4) secured, in a manner hereinafter described, to a pattern supporting table 131 of the engraving machine. The pattern 104 has a character 106 sunk therein which may be about ten times larger than the types 42 of the die. A tracer or stylus 107 engaging the pattern is secured to an arm 108 of a pentograph, not shown, which supports an engraving or routing tool 109 55

(Fig. 6) operating on the concaved surface of the die section to engrave the types 42 with flat faces thereinto.

The various patterns are secured in the same position successively, in a manner hereinafter described. Accordingly the engraving tool 109 operates always in the same area. Consequently provision is made to letter space the die section to locate it in its various letter space positions in the same line or tier of types. Provision is also made to shift said die section to any one of the tiers or rows 110, 111, and 112 of types.

To locate the die section in its various letter space positions with respect to the engraving tool 109, it is carried by an indexing sector or support 115 (Figs. 5 and 6) pivotally supported by a shaft 115^a upon a bracket 101. The die section is located on the sector 115 by dowel pins 116 mounted on said sector and extending into holes 117 of the die section; the die section being secured by screws 118 extending through holes 119 and threaded into the sector 115. The sector 115 is provided with a series of holes 120 arranged in an arc struck about the axis of the shaft 115^a and spaced angular distances corresponding to those between the types on the shuttle. A pin 121, supported in the bracket 101, is provided with a reduced end 121^a to enter any one of the holes 120 to locate and assist in holding the sector 115 in any one of its positions. A nut 122 is threaded onto the shaft 115^a by which the sector 115 may be permanently secured in its adjusted position.

Thus it will be understood that the die section is adjustable angularly to its various type positions. It will also be understood that, due to the flat pattern 106, the types 42 engraved in the die section are formed with flat faces 123 (Fig. 6) so as to produce flat faces on the types 31 on the shuttle; flat faced types being highly desirable so as to prevent buckling of the work sheet by said types while printing.

On the sector 115 there is provided a stud 116^a which extends into the groove 53 of the die sector and prevents incorrect mounting of any one of the die sections on said sector which may otherwise result in having the types upside down on one of the die sections with respect to its complement.

As illustrated in Fig. 6 the die section 33 is supported on the fixture 100 and the holes 120 to the left of the sector 115 are not used for said die section since only that portion of the die section to the right of the slot 61 therein is to be engraved. When, however, either of the adjacent die sections 32, 34 is supported in the fixture 100, the holes 120 to the left of the sector 115 are used.

For the purpose of locating the die section so as to bring any one of the various rows or tiers of types to the tool 109, there is provided a guide or gauge bar 125 secured to the table 103 by a clamp 126, said guide bar extending parallel with the axis of the shaft 115^a and being engaged by the side edge of the bracket 101. To locate the tier 110 of types, (Fig. 3) at the engraving tool 109, the bracket 101 is placed with its side edge against the guide bar 125, and its end 139^a is placed against a gauge 127 secured to the table 103 by a bolt 128. The bracket 101 is then secured in this position by the clamps 102. When the middle tier 111 of types is to be located at the engraving tool a gauge block 130, equal in width to the distance from the middle of one tier of types to the middle of the adjacent tier, is placed between the gauge 127 and the edge 130^a of the bracket 101. When the tier 112 of types is to be located at the en-

graving tool a gauge block (not shown) twice the width of the block 130 is placed between the gauge bar 127 and the edge 130^a of the die supporting bracket; the bracket being held in each of its adjusted positions by the clamps 102.

Thus it will be understood that there is provided a fixture 100 comprising a sector 115 supported by a shaft 115^a on a bracket 101 so that it may be adjusted about the axis of said shaft and relatively to the engraving tool 109, for the various types in a tier; said fixture being adjustable as a whole lengthwise of the axis of the shaft 115^a relatively to the engraving tool to shift any one of the type tiers to said tool.

The fixture 105 for holding the patterns or masters 104 may be secured to the table 131 of the engraving machine, by a pair of C-clamps 131^a (Fig. 3). Said fixture comprises a base plate 132 having a transverse groove 133 therein into which the pattern 104 may be slid from one side. A longitudinal groove 134 has a slide 135 located therein which, after the pattern is in position, is pushed by a finger-piece 136, towards the pattern plate 104 to cause a tooth 137 of the slide 135 to enter a notch 138 to lock the plate 104 against accidental lateral shifting and to position it properly on the fixture 105, the notch 138 in each pattern or templet 104 bearing a definite relation to the letter thereon. A thumb nut 139 threaded on a stud 139^a secured to the base plate 132 is then tightened to clamp said slide 135 in place. Fingers 140 and 141 on the base plate 132 and slide 135, respectively, overlap the edges of the pattern plate 104 to assist holding said plate in the groove 133. The pattern holding fixture 105 is positioned parallel to the die supporting fixture 100 and both are angularly disposed on their respective tables for clearance purposes in the machine.

The matrices or die sections are composed of 40 steel and after they have been engraved they are hardened so as to stand up subsequently in the process of manufacturing the type shuttle, said process being described in my above mentioned Patent 2,010,036.

Heretofore type shuttles have been made by first engraving a master wheel, actual size, by hand, and then using the master wheel to produce the segmental matrices, by a molding process, which matrices were subsequently used in 50 the production of the shuttle, by a further process of molding.

Said method, which requires the making of a master wheel, is not only extremely expensive but does not lend itself to the interchangeability 55 of the types, in accordance with certain desired arrangements. For example in code writing the letters on the shuttle are arranged differently although the letters on the type keys are unchanged or, in other words, arranged in their usual order. Sometimes it is also desirable to have the numerals in the top row of types on the shuttle instead of the lower row. In order to produce shuttles with these changes it has been necessary to hand engrave a new master wheel 60 which, as previously stated, is extremely expensive.

It will be understood that with the present invention these changes of the characters on the shuttle may readily be produced, at a minimum of expense, by machine engraving a set of matrices to suit the desired arrangement of types, by simply using the templets or copies 104 in the corresponding order. Thus special shuttles comprising various arrangements of characters such as letters, numbers, and marks, and also shuttles 75

with various combinations of sizes or styles of types may be readily produced at a comparatively low cost.

While certain preferred embodiments of the invention have been shown and described, it will be understood that changes in the form, arrangements, proportions, sizes and details thereof may be made without departing from the scope of the invention as defined in the appended claims.

10 I claim:—

1. In a type engraving machine, a fixture for holding a pattern to be traced by a stylus, said fixture including a stationary base plate having a transverse groove and a longitudinal groove therein, the latter extending into one side of the transverse groove, the pattern being insertable into the transverse groove from one end thereof, a slide in the longitudinal groove, a tooth on the slide to engage in a notch in the pattern to locate the pattern transversely of the fixture, fingers secured to the base plate, and fingers on the slide, all of said fingers to overlap the pattern to assist in holding the pattern in its groove, and means to clamp the slide in place on the base plate.

25 2. In a fixture for use in a machine for engraving types in a segmental die section and including with an engraving tool to operate in a definite area, the combination of a bracket having a base and an arm thereon, a die support, means to pivotally support the die support on the arm of said bracket, position determining means on said die support, means on said arm to cooperate with the position determining means to locate the die support angularly in any one of a plurality of 30 predetermined angular positions on the bracket and relatively to the engraving tool, and means to secure the die support in its adjusted position.

3. In a fixture for use in a machine for engraving a die having a concaved surface struck about 40 a center, the machine having an engraving tool adapted to operate in a definite area, and means to guide the engraving tool to cut types in the concaved face of the die, the combination of a support for said die, a bracket, means to secure 45 said bracket, a shaft by which the support is mounted on the bracket, the axis of the shaft registering with the center of the curved surface, means to locate the support and its die in various angular positions about the axis of the shaft relatively to the engraving tool, and means to secure 50 said support in its adjusted position on said bracket.

4. In a fixture for use in a machine for engraving a die having a concaved surface struck about 55 a center, the machine having an engraving tool adapted to operate in a definite area, the combination of a bracket, means to secure said bracket, a support for said die, a shaft by which the support is mounted on the bracket, the axis 60 of the shaft registering with the center of the curved surface, said support having a series of holes arranged in an arc about the axis of said shaft, a pin in said bracket to engage in any one of said holes to locate the die in various angular 65 positions relatively to the engraving tool, and means to secure the support to hold the die in its adjusted position.

5. In a fixture for use in a machine for engraving a die having a concaved surface struck about 70 a center, the machine having an engraving tool adapted to operate in a definite area, the combination of a bracket, means to secure said bracket, a shaft to mount the support on the bracket, the axis of the shaft registering with the center of curvature of the concaved surface, means to lo-

cate the support and its die in various angular positions about the axis of the shaft relatively to the engraving tool, and means to effect an adjustment of said bracket with said die lengthwise of the axis of said shaft.

5

6. In a device for use in an engraving machine, the machine having an engraving tool to operate in a definite area, a table, a pattern secured to the machine, and means including a stylus to trace the pattern to control said tool, 10 the combination of a bracket secured to said table to support a die, means to locate the bracket parallel with the pattern, and means to facilitate an adjustment of said bracket to move the die transversely of itself to various positions relatively to said tool.

15 7. In a device for use in an engraving machine, the machine having an engraving tool to operate in a definite area, a table, a pattern secured to the machine, and means including a stylus to 20 trace the pattern and control the tool, the combination of a bracket secured to said table to support a die, a gauge on said table to locate the bracket parallel to the pattern, a second gauge to engage the edge of the bracket to locate the die in a direction transversely of itself, and a 25 gauge block insertable between the edge of the bracket and the second mentioned gauge to change the position of said die relatively to the engraving tool.

30

8. In a device for use with an engraving machine, the machine having an engraving tool confined to a definite area to engrave types on the concaved face of a die, the combination of a holder to support the die, means whereby an angular adjustment of the holder may be effected to letter space the die, means to locate the die on said holder, and means to prevent incorrect mounting of the die on said holder.

35

9. In a device for use with an engraving machine, the machine having a frame, and an engraving tool confined to a definite area to engrave types on the concaved surface of a die, the combination of a holder on said frame to support the die, means whereby an angular adjustment of the holder may be effected to letter space the die, means to locate the die on said holder, means to secure the die on the holder after it has been located, and means to prevent 40 incorrect mounting of the die on the holder.

45

10. In a device for use in an engraving machine, the machine having a frame, and an engraving tool confined to a definite area to engrave types on the concaved face of a die, the combination of a holder on said frame to support the die, means whereby an angular adjustment of the holder may be effected to letter space the die, two 55 dowel pins to locate the die on said holder, and a device on said holder to engage the die to prevent incorrect mounting thereof on said holder.

60

11. In a device for use in an engraving machine, the machine having a frame, and an engraving tool confined to a definite area to engrave types on the concaved face of a die, the combination of a holder on said frame to support the die, means whereby an angular adjustment of the holder may be effected to letter space the die, means to locate the die on said holder, and a pin 65 on said holder to engage in a groove at one end of the die to prevent incorrect mounting of the die on said holder.

65

12. In a device for use in an engraving machine, the machine having a frame, and a tool to engrave a plurality of lines of adjacent types on the concaved surface of a die, the combination of 70

75

a holder on said frame to support the die, means of predetermined dimensions whereby letter spacing may be effected between the engraving tool and the holder, and means of predetermined dimensions whereby line spacing may be effected between the engraving tool and the holder.

13. A fixture for holding a pattern in a type engraving machine, said fixture including a base plate, three raised members on the upper face 10 of said base plate, two of said members being arranged parallel and spaced from each other, the third member being arranged perpendicular to the other two members and spaced from the ends of the parallel members, all of said members 15 forming a T groove on the top face of said base plate, the pattern being insertable into the head of the T groove, means to locate the pattern in the head of said T groove, a slide in the arm of the T groove, said slide engaging said pattern to 20 assist in holding the latter on the fixture, and means to secure said slide on said fixture.

14. In a type engraving machine, a fixture for holding a pattern to be traced by a stylus, said fixture including a stationary base plate having a 25 transverse groove therein into which the pattern may be inserted from one end thereof, said base plate having also a longitudinal groove extending into only one side of the first mentioned groove,

a slide supported in and guided by the longitudinal groove, means on said slide to locate said pattern lengthwise of said transverse groove, said slide being also effective to hold the pattern against the opposite side of the transverse groove, 5 and means to secure the slide in its effective position to assist in preventing accidental displacement of said pattern.

15. In a type engraving machine, a fixture for holding a pattern to be traced by a stylus, said fixture including a stationary base plate having a transverse groove therein into which the pattern may be inserted from one end thereof, said base plate having also a longitudinal groove extending into only one side of the transverse groove, a 15 slide supported in the longitudinal groove, means on said slide to locate the pattern in a definite position lengthwise of the transverse groove, said slide being also effective to hold the pattern against the opposite side of the transverse slot, 20 means on the base plate to overlap one edge of the pattern, means on said slide to overlap the opposite edge of said pattern to assist in holding the pattern in the groove, and means to secure said slide in its effective position to assist in 25 preventing accidental displacement of said pattern.

HENRY L. PITMAN.
